UNITED STATES PATENT OFFICE.

WHITCOMB L. JUDSON, OF MINNEAPOLIS, MINNESOTA, ASSIGNOR TO THE JUDSON PNEUMATIC STREET RAILWAY COMPANY, OF SAME PLACE.

UNIVERSAL JOINT.

SPECIFICATION forming part of Letters Patent No. 423,562, dated March 18, 1890.

Application filed June 28, 1889. Serial No. 315,901. (No model.)

To all whom it may concern:

Be it known that I, WHITCOMB L. JUDSON, a citizen of the United States, and a resident of the city of Minneapolis, county of 5 Hennepin, State of Minnesota, have invented a certain new and useful Improvement in Universal Joints, of which the following is a specification, reference being had to the accompanying drawings.

10 My invention was especially designed for use in connection with the converting mechanism applicable to the propulsion of street-railways and other carriages of the character set forth in the United States Letters Patent 15 issued to me on May 7, 1889, numbered, respectively, 402,674, 402,933, and 402,934. It is, however, capable of use elsewhere, whenever it is desirable to couple together a sectional shaft so that the sections may be capable 20 of angular and curvilinear adjustment with respect to each other.

In carrying out my invention I construct the separate sections with telescoping or interlocking ends having roller-bearings between the telescoping parts. The telescoping parts are preferably of clutch-like form, and the roller-bearings are cones mounted on a central shaft, or radial pins extending outward from a central roller or barrel. The 30 great advantages of this construction are that the sections may be curved to a very short radius or take any desired angular relation, while the whole friction is taken on the roller-bearing, and the separate sections may be 35 readily detached for removal and replacement at will.

In the drawings, like letters referring to like parts, Figure 1 is a plan view of my invention in working position. Fig. 2 is a longitudinal vertical section of the same. Fig. 3 is a plan view of a pair of shaft-sections and the roller-bearings detached. Fig. 4 is an end view of one of the clutch-heads with roller-bearings in position. Fig. 5 is an end view of clutch with roller-bearing.

40 A A' A'' represent separate shaft-sections. a represents the journals of the same.

B are the clutch-heads, each of which is provided with jaws or telescoping parts b, 45 adapted to engage with each other. One pair

of diametrically-opposite jaws on each clutch-head are cut away on their opposite faces to form seats b' for the roller-bearings.

C is the center piece of the roller-bearings, which, as shown, is barrel-shaped, and is provided with radial pins c, on which are mounted the cone-shaped rollers D. The center piece rests in the spaces between the pairs of clutch-heads and the cone-shaped bearings in the seats b'. 55

60 The projecting jaws of each clutch-head are substantially wedge shape in cross-section, as shown in Figs. 4 and 5, and are formed on lines radiating from a common center. The space between the inner truncated ends 65 of the jaws is just sufficient to admit the center piece C freely, and the seats or cut-away portions b' of the two diametrically-opposite jaws form shoulders to prevent endwise movement of the center piece and its radial pins 70 and rollers. The pins or shafts supporting the conical rollers do not receive any part of the strain, which is wholly sustained by the interlocking jaws and the rollers fitting snugly therebetween. 75

I am aware that universal joints provided with interlocking ends and roller-bearings are not broadly new.

It will of course be understood that the journals a a of each shaft-section are to be so 80 mounted in suitable boxes as to freely rotate therein, said boxes preventing endwise movement of the sections, and thereby keeping their clutch ends in engagement.

As shown, the shaft is a hollow drum; but 85 of course it might equally well be solid.

What I claim, and desire to secure by Letters Patent of the United States, is as follows:

1. A shaft composed of separate sections, each provided with a journal at one end and 90 a clutch-head carried by said journal, and each having a clutch-head at the opposite end, and roller-bearings mounted between each pair of clutch-heads, substantially as set forth. 95

2. The combination, with the shaft-sections provided with projecting jaws at each end, two diametrically-opposite jaws being cut away to form bearing-seats, as described, of a center piece placed between the inner ends 100

of the jaws and having projecting pins, and cone-shaped rollers mounted on the pins, substantially as described.

3. The combination, with the shaft-sections having projecting jaws at each end, with a clear central space between the jaws, two diametrically-opposite jaws being cut away to form seats, of a barrel-shaped center piece

mounted in the said space, and cone-shaped rollers on pins projecting from the center piece and located in said seats, substantially as set forth.

WHITCOMB L. JUDSON.
